UNITED STATES PATENT OFFICE.

JOHN RAU, OF INDIANAPOLIS, INDIANA.

VALVE MECHANISM.

1,325,331.

Specification of Letters Patent.

Patented Dec. 16, 1919.

Application filed January 12, 1917. Serial No. 142,023.

To all whom it may concern:

Be it known that I, JOHN RAU, a citizen of the United States, and a resident of Indianapolis, county of Marion, and State of

5 Indiana, have invented a certain new and useful Valve Mechanism; and I do hereby declare that the following is a full, clear, and exact description thereof, reference being had to the accompanying drawings, in
10 which like letters refer to like parts.

The object of this invention is to facilitate and render more convenient the operation of machines for forming blanks for hollow glassware.

15 The chief feature of the invention resides in a single valve mechanism arranged so as to control the various parts of the machine in operation, and at the same time lock and unlock the table on which the molds are
20 mounted. To that end the movable valve member also serves as a bolt or means for locking and unlocking the table and when it is moved into position to lock the table, the valve or locking means automatically
25 opens certain ports for the passage of compressed air which will cause the various steps of the operation of the machine, as is desired when the table is in locking position. Thus it will introduce compressed air into
30 the blank mold for pressing down the body of the glass around the former to form the mouth and neck of the mold or blank. At the same time it will blow a blow opening in a blank in another blank mold. It will
35 also actuate or spring into place a baffle head in connection with the mold in which the blow opening is being formed in the blank. On the other hand, when the movable valve member is moved out of locking en-
40 gagement with the table, it will change the condition of the ports so as to bring about the proper exhaust for all of the air cylinders for actuating the plungers, blow pipe and baffle head above referred to.

45 This renders the device very simple in operation as all that is necessary is to move the mold table step by step in the proper position and then actuate the valve which, as stated, locks the table in true position
50 and opens the compressed air ports so as to permit the proper passage of the air to the parts as above stated.

There are, in addition to the foregoing, several other features of invention as will
55 hereafter appear.

The full nature of the invention will be understood from the accompanying drawings and the following description and claims.

In the drawings, Figure 1 is a front elevation of the machine with parts in actuated position. Fig. 2 is an elevation of the right hand side of the machine with parts in idle position and parts broken away. Fig. 3 is a vertical section on the line 3—3 of Fig. 60 2, but on a larger scale and with parts in modified position. Fig. 4 is a horizontal section on the line 4—4 of Fig. 3. Fig. 5 is a vertical section on the line 5—5 of Fig. 65 1, part being shown in elevation. Fig. 6 70 is a similar section on the line 6—6 of Fig. 2, with the parts in their operated positions and a part partly in section and partly in elevation. Fig. 7 is a section on the line 7—7 of Fig. 2. Fig. 8 is a diagrammatic 75 view of the more important parts of the machine showing their relative relations and some said parts being shown in section as indicated.

There is shown herein a base 10 upon 80 which a hollow stand 11 is mounted which is integral with a central and upwardly extending hollow column 12 of smaller diameter. These two hollow members 11 and 12 form a single compressed air chamber into which 85 air enters through a pipe 13 from some suitable source of compressed air and from which air is supplied to the various portions of the machine, as hereinafter explained.

There is a rotary mold table 15 mounted 90 by ball bearings 16 on a top flange 17 at the upper end of the stand 11. Upon said mold table there is mounted an annular series of press molds 18. The molds, in the machine here shown, are formed as indicated in Figs. 5 and 6, being inverted with the cavity of the hole extending entirely through the same vertically and being larger at the upper end of the mold and tapering downward. The lower end of the mold is 100 annularly recessed to fit around a segmental ring 20 secured upon the table. The lower end of the mold is also recessed to receive a neck mold or lift-over 21 for forming the neck of the glass blank 22.

105 In this machine the blank is formed with the mold in inverted position so that the neck of the blank is downward and the upper end of the mold is open and enlarged so that the gather of glass can be inserted 110

into the upper end of the mold, as shown in Fig. 5, and then the neck of the blank is formed at the lower end of the mold, by one operation, as illustrated in Fig. 5, and afterward an enlarged blow opening 23 is formed in the blank, as indicated in Fig. 6. Thereafter the blank is transferred to a blow mold, which is not here shown, and blown until the article is completed.

- 10 The table is rotated until one of the holes 24 through the mold table 15 comes in registry with a top plunger 25 on the upper end of a piston valve 26 mounted in a valve casing formed of two parts, 27 and 127. 15 Said casing is vertically supported by a bracket 28 extending from the flange 17 on the top of the stand 11 and it slidably operates at its lower end through a bar 29 extending from the base 10 and in it the valve 20 is keyed so that it cannot turn, but can move vertically. It is forced upward or actuated by a spring 30 which surrounds the lower part of the valve and lies between the bar 29 and a collar 31 on the valve. The 25 valve is returned or depressed by a pedal lever 32 acting downwardly upon the collar 31 which is fulcrumed on its end at 33 in the upper end of a post 34 mounted on the base 10. Action on the pedal lever depresses 30 the valve 26 and stop 25 so as to move it out of engagement with the mold table until the table has been rotated so as to bring another mold into proper position and then the pedal is released and the spring 30 forces 35 the valve 26 upward and the stop 25 engages a hole 24 in the table 15 and holds it temporarily.

The valve casing is formed of two vertical halves or parts 27 and 127, indicated 40 by cross section in Fig. 4, which together surround the valve and are held together by bolts 40, see Fig. 1. Bolts 41 secure the casing to the support 28. A stuffing box 42 is mounted on the lower end of the casing 45 and the stuffing box 43 is mounted on an upper projection 44 on the support 28, as seen in Fig. 3.

There is an exhaust passage 45 longitudinally of the valve in communication with 50 three transverse exhaust passageways 46 extending diametrically through the valve.

The valve mechanism controls the passage of air from the air reservoir in the hollow columns 11 and 12 for the various 55 parts of the machine, as made clear in the diagram in Fig. 8. From said reservoir a pipe 50 leads to a port 51 in the valve casing, as shown in Fig. 3. There is also another pipe 52 leading from the reservoir to 60 a port 53 in the valve casing. There is also a pipe 54 in communication with a port 55 which at times is in communication with the port 51 through a port 56 in the valve, when said valve is in the position shown in 65 Fig. 3. That occurs during the formation

of the blanks. There is also a pipe 57 communicating with a port 58 in the casing and associated with the port 53 by means of a port 59 in the valve, as shown in Fig. 3. There is also a pipe 60 communicating with 70 a port 61 in the valve and a pipe 62 communicating with a port 63 in the valve.

To a bracket 64 secured to the flange 17, as shown in Fig. 1, there is connected an air cylinder 65 in which a press plunger 66 is 75 located and said plunger has a plunger head 67 adapted to register with and pass through a hole 68 in the table 15, as seen in Fig. 5. The air pipe 54 leads from the valve mechanism heretofore described to the bottom of 80 said cylinder and the exhaust pipe 60 leads from the upper end of said cylinder to the valve mechanism. The plunger head 67 is hollow, as shown in Fig. 5, and it is cooled by air entering it through a pipe 70 which 85 leads from the hollow air stand 11. The air exhausts from the head 67 through exhaust outlets 71.

In the vertical alignment with the plunger cylinder 65 and located above the mold table 90 there is mounted a blow head 73 adapted to close the upper end of the mold, as shown in Fig. 5 and enable the air coming through the blow head to blow the gather of glass 95 downward for forming the neck of the blank and solidifying the blank. Said blow head is secured to the lower end of a tube 74 vertically slidably in an arm 75 extending from a collar 76 slidably mounted on the column 12 and held in adjusted position by means 100 not shown. The pipe 74 is held elevated by a spring 77 surrounding it and resting upon the arm 75 below and against a collar 78 on the upper part of the tube 74. The tube 74 and blow head are depressed by a hand 105 lever 79 which rests upon the collar 78 of the tube and at its inner end at 80 is fulcrumed to a post 81 extending up from the collar 76. The upper end of the tube 74 is connected by a flexible tube 82 with the upper part of the air column 12, as seen in Fig. 1.

The plunger cylinder 65 is about 90° from the valve mechanism. Immediately behind the valve mechanism and, therefore, 115 about 90° from the plunger cylinder heretofore described there is another air cylinder 85 mounted on the arm 28 and in connection with the valve casing 27, as seen in Fig. 2, and having in it to be operated by it a tubular plunger 86 from the upper end of which a blow pipe 87 projects. The plunger tube 86 and blow pipe 87 are in alignment with one of the holes 68 when the mold table is stopped and held by the stop 25, 120 as shown in Fig. 6. Air is supplied to the lower end of the cylinder 85 through a pipe 88 which leads from the pipe 57 and then air is exhausted from the upper end of said cylinder through a pipe 89 which leads to 125 130

the pipe 62. An air pipe 191 leads from the air stand 11 to the lower end of the tubular plunger 86 for supplying air through the blow pipe 87. When the parts are in 5 the position shown in Fig. 6, air coming through the blow pipe 87 forms the blow opening 23 in the blank, as therein shown. During such operation the upper end of the mold is closed by a baffle plate or head 91 10 on the lower end of a rod 92 vertically reciprocable in an air cylinder 93 mounted on a bracket 94 extending from the collar 76, as seen in Fig. 2. Air is supplied by the upper end of the cylinder 93 through a pipe 15 95 extending from the air column 12 and in direct communication with the pipe 57 below. An air pipe 96 connects the lower end of the cylinder 93 with the pipe extending through the column 12 in communication 20 with the pipe 62 below. Pipes 50 and 52 have hand operated valves 97, as seen in Figs. 1 and 2, for closing the same when the machine is not in operation.

Operation: When it is desired to operate 25 the machine the valves 97 are opened admitting the compressed air for operating the machine. A mold on the mold table in advance of the blow head 73 is supplied with a gather of glass which is inserted in 30 the upper end of the mold, as shown in Fig. 5. Then the table is moved to bring said mold under said blow head 73 and during such movement of the table, the foot lever 32 is held depressed by holding the stop 25 35 away from the table. When the mold is brought under the blow head 73, the hole 24 in the table will be over the stop 25 and by releasing the pedal lever 32, the spring 30 will force the valve 26 upward and the 40 stop 25 will enter the hole 24 of the table and hold the table in fixed and true position. Such upward movement of the valve will bring it into the position shown in Fig. 3 and establish communication between 45 pipes 50 and 54 so that compressed air from the reservoir in the stand 11 or column 12 will enter the cylinder 65 and move the plunger head 67 up into the lower end of the mold, as shown in Fig. 5, to form the neck 50 of the blank. At the same time the operator pulls down on the lever 79, see Fig. 1, and brings the blow head 73 down on the mold, closing the upper end thereof, and through air entering the pipes 82 and 74 upon the 55 upper end of the glass in the mold, the glass is forced down around the plunger head 67 and that makes the body of glass compact and causes the neck of the blank to be pressed satisfactorily.

60 After the above step in the operation is completed, the operator depresses the pedal lever 32 and releases the hand lever 79 which causes the removal of the plunger head 67 and the blow head 73. Then the table is 65 moved another step until said previously

filled mold is brought beneath the baffle plate 91 and a second mold previously supplied with a gather of glass is brought under the blow head 73. Then upon the release of the pedal lever and the upward 70 movement of the valve 26 communication will again be established between pipes 50 and 54 and between pipes 52 and 57. The second gather of glass will be treated in the manner above described and the properly 75 formed blank in the first mentioned mold which is now under the baffle plate 91 will be treated as shown in Fig. 6. That is, air passing through pipes 52 and 57 will enter the cylinder 85 and move the tubular plunger 86 upward to bring the tube 87 into the mouth or lower end of the mold, as shown in Fig. 6, and at the time the air in said pipe 57 will pass upward through the stand 11 and column 12 and through pipe 95 and 80 depress the baffle plate 91. The baffle plate 91 seats in the upper end of the mold, as shown in Fig. 6. The upward movement of the tube 86 opens communication with pipe 191, as shown in Fig. 7, and thus air 90 is introduced into the lower end of the blank 22, as seen in Fig. 6, and a large blow opening 23 formed therein extending preferably throughout the greater length of the blank or mold. This is particularly desirable for large hollow glassware. It is noted that the tube 191 does not communicate with the tubular pipe 86 excepting when the latter is elevated as shown in Fig. 7.

The formation of the blanks of this machine include two steps in the operation. While one step of the operation is being performed on one blank, the other step is being performed on another blank whereby the external form of the blank is determined 100 and particularly the neck thereof. In the second step the internal form of the blank is determined and without removing the blank from the mold.

When the valve 26 is depressed by the 110 pedal lever the compressed air communicates between pipes 50 and 54 and the pipes 52 and 57 are disconnected and then the upper exhaust passage 46 is in registry with the tube 54. The middle exhaust passage 115 46 is in registry with the tube 57, while the lower passage 46 is cut off from communication with pipe 62. When the valve is elevated the lower exhaust passage 46 is in communication with pipe 62 and the middle 120 exhaust passage 46 with the pipe 60. The exhaust passages are relatively small and are for the purpose of relieving undue air pressure and particularly exhausting the cylinders 65 and 85.

When the valve 26 is in its elevated position, as shown in Fig. 3, it causes simultaneous actuation of the plunger for forming the mouth of the mold of the blank, as in Fig. 5, as pipes 50 and 54 are in communica- 130

tion with each other, and simultaneous action of the tubular plunger 86 and blow pipe 87, and also baffle plate 91 as pipes 52 and 57 are in communication with each other.

- 5 While the valve is in its upper position, the middle exhaust passage 46 communicates with pipe 60 which exhausts the upper end of the cylinder 65. Also the exhaust passage 46 is in communication with pipe 62
 10 10 whereby the upper end of the cylinder 85 and the lower end of the cylinder 93 are exhausted.

Also when the valve is in its lower position, the chamber 56 therein connects
 15 pipes 50 and 60 whereby the plunger 66 is positively returned to its lower position; also chamber 59 connects pipes 52 and 62 which positively returns the tubular plunger 86 and blow pipe 87 and also returns
 20 and elevates the baffle head 91.

Thus it is seen that the operation of this machine may be very rapid and it may be operated by a single operator. Aside from his turning the mold table with one hand, 25 depressing the valve with his foot while he is turning the table and bringing down the blow head with his other hand, all the other parts and operations of the machine are automatic and capable of rapidly turning
 30 out work.

Attention should be called to another feature of the invention which is disclosed in Fig. 4, namely, that the valve member 26 is more deeply seated in the part 27 of the
 35 valve casing than the part 127. That is, the seal or recess in the part 27 extends more than half way about the valve 26 so that said valve will be held in place in the casing member 27 when the other casing member 40 127 may be, for any purpose removed. All of the ports above referred to are also located in the casing 127 so that by removing said casing member you can get into all of the ports of the valve mechanism.

45 The invention claimed is:

1. A glass blank forming machine including a rotatable table, a plurality of blank molds thereon, a plunger for pressing the mouth and neck of the blanks in said molds, 50 a cylinder for actuating said plunger, a blow pipe for introducing air into the mouth of a blank after it has been pressed to form a blow opening in the blank, a cylinder for moving said blow pipe into blowing position, 55 a source of compressed air, and a valve mechanism for controlling the air and arranged in one position to engage and hold the table from rotation and when in such position to permit the admission of air to
 60 one end of each of said cylinders for actuating said plunger and blow pipe and at the same time to exhaust the air from the other end of each of said cylinders and when in position to disengage said table, to permit the admission of air into the last-mentioned end of each of said cylinders and to exhaust it from the other end thereof for returning said plunger.
- 65 2. A glass blank forming machine including a rotatable table, a plurality of blank molds thereon, a plunger for pressing the mouth and neck of the blanks in said molds, a cylinder for actuating said plunger, a blow pipe for introducing air into the mouth of a blank after it has been pressed to form a blow opening in the blank, a cylinder for moving said blow pipe into blowing position, a source of compressed air, a baffle head for

end of each of said cylinders and to exhaust it from the other end thereof for returning said plunger.

2. A glass blank forming machine including a rotatable table, a plurality of blank molds thereon, a plunger for pressing the mouth and neck of the blanks in said molds, a cylinder for actuating said plunger, a blow pipe for introducing air into the mouth of a blank after it has been pressed to form a blow opening in the blank, a cylinder for moving said blow pipe into blowing position, a source of compressed air, a valve mechanism for controlling the air and arranged in one position to engage and hold the table from rotation and when in such position to permit the admission of air to one end of each of said cylinders for actuating said plunger and blow pipe and at the same time to exhaust the air from the other end of each of said cylinders and when in position to disengage said table, to permit the admission of air into the last-mentioned end of each of said cylinders and to exhaust it from the other end thereof for returning said plunger, a spring for forcing said valve into engagement with said table, and a lever for disengaging said valve from the table and holding it disengaged.

3. A glass blank forming machine including a rotatable table, a plurality of blank molds thereon, a plunger for pressing the mouth and neck of the blanks in said molds, a cylinder for actuating said plunger, a blow pipe for introducing air into the mouth of a blank after it has been pressed to form a blow opening in the blank, a cylinder for moving said blow pipe into blowing position, a source of compressed air, a baffle head for closing the upper end of the mold while the blow opening is being formed in the blank, a cylinder for actuating the same, and a valve mechanism for controlling the air and arranged in one position to engage and hold the table from rotation and when in such position to permit the admission of air to one end of each of said cylinders for actuating said plunger and blow pipe and at the same time to exhaust the air from the other end of each of said cylinders and when in position to disengage said table, to permit the admission of air into the last-mentioned end of each of said cylinders and to exhaust it from the other end thereof for returning said plunger.

4. A glass blank forming machine including a rotatable table, a plurality of blank molds thereon, a plunger for pressing the mouth and neck of the blanks in said molds, a cylinder for actuating said plunger, a blow pipe for introducing air into the mouth of a blank after it has been pressed to form a blow opening in the blank, a cylinder for moving said blow pipe into blowing position, a source of compressed air, a baffle head for

closing the upper end of the mold while the blow opening is being formed in the blank, a cylinder for actuating the same, a valve mechanism for controlling the air and arranged in one position to engage and hold the table from rotation and when in such position to permit the admission of air to one end of each of said cylinders for actuating said plunger and blow pipe and at the same time to exhaust air from the other end of each of said cylinders and when in position to disengage said table, to permit the admission of air into the last-mentioned end of each of said cylinders and to exhaust it from the other end thereof for returning said plunger, a spring for forcing said valve into engagement with said table, and a lever for disengaging said valve from the table and holding it disengaged.

In witness whereof I have hereunto affixed my signature.

JOHN RAU.
